UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed July 28, 1923. Serial No. 654,306.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

The invention relates to typewriting machines having so-called wing-scales, for exhibiting letter-space readings above the upper edge of the ribbon, immediately at the side of the printing point; and to machines in which, at each type-stroke, the ribbon is 15 vibrated to cover the printing point.

The wing-scales are ordinarily set closely to the platen behind the ribbon and ribbon-vibrator-guide, and heretofore have been formed on a plate secured to the rear face of 20 the ribbon-vibrator-guide. The latter, in turn, has been secured to the front rail of the platen-shift-frame. Such a mounting of the wing-scale-plate has been entirely satisfactory for ordinary work. It is sometimes 25 desired, however, to use the machine for the cutting of stencils, and the stencil-pieces are commonly mounted in card-board frames of considerable thickness and stiffness. Often only two or three lines are required to be 30 written on the stencil-cards, and insertion of the cards downward between the wing-scales and the platen, at the front of the machine, is the most convenient and expeditious manner of introducing the cards. In this use of 35 the machine, and, owing to the thickness and stiffness of the card-frames, the cards may be jammed or unduly crowded by the wing-scale-plate if the latter lies between the ribbon-vibrator-guide and the platen. Fur- 40 thermore, if, contrary to the present practice, the cards may be passed down between the wing-scale-plate and the platen with sufficient ease, it becomes practicable to employ certain simple devices as stops or gages 45 to determine the initial setting of the card in the machine.

A feature of the invention is the provision of a wing-scale-plate of such shape that, although the wing-scales may lie in normal 50 position behind the ribbon and ribbon-vibrator-guide, the plate may nevertheless be mounted on the front of the ribbon-vibrator-guide, and the passage between the ribbon-vibrator-guide and the platen thus be cleared 55 for easy front-insertion of cards. Prefer-

ably the plate comprises a base or body-piece at the front of the ribbon-vibrator-guide and scale-carrying arms bowed laterally therefrom around and to the rear of the ribbon-vibrator-guide. A feature of the invention is a bowing of the scale-carrying arms in such wise as to provide a long reach thereof between the scales and the points of attachment of the plate; so that, the arms, being of spring-material, will yield readily 60 to allow thick cards to be passed freely between the scales and the platen.

A feature of the invention is the provision of stops or gages to determine an initial setting of the cards, from which setting the 70 cards may be line-spaced for the writing of several lines thereon; and the provision of a mounting for the wing-scale-plate, such that the cards may be freely passed down, 75 at the front of the platen, between the platen and the ribbon-vibrator-guide, until they come to rest on such stops or gages. Preferably the stops or gages are formed on the ribbon-vibrator-guide, and it is a further feature of the invention that the fingers, 80 which have heretofore been employed to hold the carriage to its seat on the shift-frame, may serve as the stops or gages for the cards.

Other features and advantages will here- 85 inafter appear.

In the accompanying drawings,

Figure 1 is a front view of the carriage and associated parts of a typewriting machine equipped according to the present in- 90 vention.

Figure 2 is a view in side elevation, partly cross-sectional, of the apparatus shown in Figure 1.

The platen 10 is journaled in the side 95 plates 11 of a carriage 12, movable in letter-feed and return directions on a shift-frame 14. The shift-frame 14 is mounted, and is movable between case-positions, on the main frame 15 by mechanism (not shown), but 100 which may be similar to that shown in United States Letters Patent to William A. Dobson, No. 1,335,956, dated April 6, 1920. A rail (not shown) provides a support and runway, at the rear, for the carriage on the 105 shift-frame. A cross-tie 17, forming part of the carriage, below the platen, forms a rail, by means of which the carriage is supported at its forward portion on rollers 18 on a rail or runway 19 on the shift-frame. 110

The rail 17 is secured by screws 20 to ears 21 offset from the side pieces 11 of the carriage 12.

A ribbon-vibrator-guide 22, such as is found in the Underwood standard portable machine, is secured by screws 23 to the rail 19. The ribbon-vibrator-guide comprises a lower cross-piece 24, inclined portions 25 and vertically-disposed fingers 26, on which the ribbon-vibrator has movement up and down. The vertical fingers 26 are offset slightly forward from the inclined portions 25 of the ribbon-vibrator-guide to provide space for the upper portion of the wing-scale or scale-shield 27 and ribbon-vibrator. Offset rearward from the upper edge of the cross-portion 24 of the ribbon-vibrator-guide are a pair of fingers 28 which overlie the upper edge of the carriage-rail 17, and thus hold the carriage to the rail 19 of the shift-frame.

The scale-shield 27 is shown as comprising a lower cross-piece 29 and two arms 30 which extend upward and carry the wing-scales 31. It has been noted that the wing-scales 31 lie between the ribbon-vibrator-guide and the platen. The cross-piece 29, however, lies in front of the ribbon-vibrator-guide, and the arms 30 are turned laterally from the wing-scales with a slight forward offset at 32, beyond the side edges of the fingers 26 of the ribbon-vibrator-guide, and are thence extended downward on a long curve to join the cross-portion 29. From the cross-piece 29 of the shield two fingers 33 are extended vertically upward, and, at their upper ends, are perforated at 34, to receive screws 35, by means of which the shield is secured to the front face of the ribbon-vibrator-guide at the junction of the vertical fingers 26 and inclined portions 25 of the latter.

As hereinbefore noted, the shield has heretofore been secured to the rear face of the ribbon-vibrator-guide. By curving the arms 30, however, so that the lower portion of the scale-shield may be located at the front of the ribbon-vibrator-guide, the obstruction of such lower portion of the scale-shield, heretofore offered to passage of cards downward at the front of the platen, is removed; and, as shown in the drawings, the card 36 may be passed freely down until its lower edge strikes the fingers 28 on the ribbon-vibrator-guide which hold the carriage to the shift-frame. These fingers 28, therefore, serve as a seat or gage for determining the initial position of the card. The fingers 28 are sufficiently far below the printing line to permit of the writing of two or three lines on the card or stencil, without bringing the lower margin of the card to the printing line on line-space-feed of the platen in the usual direction. Furthermore, the long goose-neck curvature of

the arms 30 of the scale-shield provides flexibility of these arms such as to permit them to yield readily for the passage of thick cards between the wing-scales and the platen.

Paper-fingers 37, mounted on a scale-bar 38, which latter is secured at the front of the platen to ears 13 formed on the front lower edge of the usual paper-table 16, may be adjustable along such scale-bar 38 to position to hold the card by its side margins to the platen, as shown in Figure 1 of the drawings.

Variations may be resorted to within the scope of the invention, and portions of the improvements may be used without others.

Having thus described my invention, I claim:

1. In a typewriting machine, a platen, a carriage for the platen, a frame on which the carriage has movement in letter-feed and return directions, a ribbon-vibrator-guide on the frame at the front of the platen, a wing-scale behind the ribbon-vibrator-guide, and means for supporting the scale on the front of the ribbon-vibrator-guide.

2. In a typewriting machine, a platen, a carriage for the platen, a frame on which the carriage has movement in letter-feed and return directions, a ribbon-vibrator-guide on the frame at the front of the platen, a wing-scale behind the ribbon-vibrator-guide, and means for supporting the scale on the front of the ribbon-vibrator-guide, comprising an arm offset forward from the scale and extending downward to the lower part of the ribbon-vibrator-guide.

3. In a typewriting machine, a platen, a carriage for the platen, a frame on which the carriage has movement in letter-feed and return directions, a ribbon-vibrator-guide on the frame at the front of the platen, a wing-scale behind the ribbon-vibrator-guide, and means for supporting the scale on the front of the ribbon-vibrator-guide, comprising an arm having a lateral bend from the scale to the base of the ribbon-vibrator-guide.

4. In a typewriting machine, a platen, a carriage for the platen, a frame on which the carriage has movement in letter-feed and return directions, a ribbon-vibrator-guide on the frame at the front of the platen, a wing-scale behind the ribbon-vibrator-guide, and means for supporting the scale on the front of the ribbon-vibrator-guide, comprising an arm attached to the ribbon-vibrator-guide and curved laterally down from the wing-scale to a point below its point of attachment to the ribbon-vibrator-guide and thence up to such point of attachment.

5. In a typewriting machine, a platen, a carriage for the platen, a frame on which the carriage has movement in letter-feed

and return directions, a ribbon-vibrator-guide on the frame at the front of the platen, a wing-scale behind the ribbon-vibrator-guide, and means for supporting the 5 scale on the front of the ribbon-vibrator-guide, comprising a resilient arm having a lateral bend from the scale to the base of the ribbon-vibrator-guide.

6. In a typewriting machine, a platen, a 10 carriage for the platen, a frame on which the carriage has movement in letter-feed and return directions, a ribbon-vibrator-guide on the frame at the front of the platen, comprising a base-piece and guide-fingers 15 extending upward therefrom, and a wing-scale-plate comprising a cross-arm or base-piece, and arms bowed laterally outward, from either end thereof, upward over the front of the ribbon-vibrator-guide base-piece, thence inward behind the guide-fingers of the ribbon-vibrator-guide, and having on their ends the wing-scale.

7. In a typewriting machine, a platen, a carriage for the platen, a frame on which the carriage has movement in letter-feed and return directions, a ribbon-vibrator-guide on the frame at the front of the platen, comprising a base-piece and guide-fingers extending upward therefrom, and a wing-scale-plate comprising a cross-arm or base-piece, and arms bowed laterally outward, from either end thereof, upward over the front of the ribbon-vibrator-guide base-piece, thence inward behind the guide-fingers 35 of the ribbon-vibrator-guide, and having on their ends the wing-scale; the cross-arm or base-piece of the wing-scale-plate having upwardly-projecting ears for attachment of the plate to the ribbon-vibrator-guide intermediate the upper and lower ends of the wing-carrying arms.

8. In a typewriting machine, a platen, a carriage for the platen, a frame on which the carriage has movement in letter-feed and return directions, a ribbon-vibrator-guide on the frame at the front of the platen, a wing-scale behind the ribbon-vibrator-guide, means for supporting the scale on the front of the ribbon-vibrator-guide, and means at 50 the rear of the ribbon-vibrator-guide for engagement with the lower edge of a card inserted downward between the guide and the platen, to arrest the card in a given position.

55. 9. In a typewriting machine, a platen, a carriage for the platen, a frame on which the carriage has movement in letter-feed and return directions, a ribbon-vibrator-guide on the frame at the front of the platen, a wing-scale behind the ribbon-vibrator-guide, means for supporting the scale on the front of the ribbon-vibrator-guide, and shoulders 60 on the rear of the ribbon-vibrator-guide for engagement with the lower edge of a card

inserted downward between the guide and the platen, to arrest the card in a given position.

10. In a typewriting machine, a platen, a carriage for the plate, a frame on which the carriage has movement in letter-feed and return directions, a ribbon-vibrator-guide on the frame at the front of the platen, a wing-scale behind the ribbon-vibrator-guide, means for supporting the scale on the front of the ribbon-vibrator-guide, and fingers 70 turned rearward out of the ribbon-vibrator-guide for engagement with the lower edge of a card inserted downward between the guide and the platen, to arrest the card in a given position. 75

11. In a typewriting machine, a platen, a carriage for the platen, a shift-frame, having side plates, and a rail connecting the side plates at the front thereof, on which the carriage has movement in letter-feed and return directions, a ribbon-vibrator-guide secured to the rail at the front of the platen, a wing-scale behind the ribbon-vibrator-guide, and means for supporting the scale on the front of the ribbon-vibrator-guide. 80 85

12. In a typewriting machine, a platen, a carriage for the platen, a frame on which the carriage has movement in letter-feed and return directions, a ribbon-vibrator-guide on the frame at the front of the platen, a wing-scale behind the ribbon-vibrator-guide, means for supporting the scale on the front of the ribbon-vibrator-guide, a bar on the carriage extending longitudinally of the platen at the front of the latter, and paper-fingers adjustable lengthwise of such bar to position to engage and hold to the platen the margins of a card inserted between the ribbon-vibrator-guide and the platen. 90 95 100

13. In a typewriting machine, a platen, a carriage for the platen, a frame on which the carriage has movement in letter-feed and return directions, a ribbon-vibrator-guide on the frame at the front of the platen, a wing-scale behind the ribbon-vibrator-guide, means for supporting the scale on the front of the ribbon-vibrator-guide, means at the rear of the ribbon-vibrator-guide for engagement with the lower edge of a card inserted downward between the guide and the platen, 110 to arrest the card in a given position, a bar on the carriage extending longitudinally of the platen at the front of the latter, and paper-fingers adjustable lengthwise of such bar to position to engage and hold to the platen 115 the margins of a card arrested as aforesaid by said means at the rear of the ribbon-vibrator. 120
